FIG.1

FIG.2

FIG.4

FIG.3

FIG.5

FIGURE 1 is a front perspective view of a gun cleaning equipment container showing my new design in an open condition;

FIGURE 2 is a top plan view thereof;

FIGURE 3 is a rear elevational view thereof;

FIGURE 4 is a side elevational view thereof, the opposite side being substantially identical therewith; and

FIGURE 5 is a side elevational view similar to FIGURE 4, with the cover of the container in closed position.

The characteristic feature of my design resides in the combination in the box disclosed of the particular compartments which are arranged about the sides and back as shown.

I claim:

The ornamental design for gun cleaning equipment container, substantially as shown and described.
